UNITED STATES PATENT OFFICE.

WADE H. HARRISS, OF HOUSTON, TEXAS.

BRAKE FOR MARINE VESSELS.

1,196,682.

Specification of Letters Patent. Patented Aug. 29, 1916.

Application filed March 3, 1916. Serial No. 81,947.

To all whom it may concern:

Be it known that I, WADE H. HARRISS, a citizen of the United States of America, residing at Houston, in the county of Harris and State of Texas, have invented new and useful Improvements in Brakes for Marine Vessels, of which the following is a specification.

This invention relates to brakes for marine vessels, the broad object in view being to provide in connection with the hull of a marine vessel, one or more shiftable brakes located on each side thereof together with operating means whereby one or more of the brakes may be moved outwardly to braking position or moved inwardly to a position where the body of the brake is substantially flush with the outer surface of the hull of the vessel.

20 The particular object of the present invention is to produce a brake of the character referred to which is unusually effective and which, by reason of the mounting thereof, will obtain a greater suction or offer a 25 greater resistance to the forward movement of the vessel thereby the sooner bringing said vessel to a stop. The brakes at opposite sides of the boat may also be utilized on either side of the vessel for directional purposes or for causing the vessel to turn in one 30 direction or the other.

With the above and other objects in view, the invention consists in the novel construction, combination and arrangement of parts, 35 as herein described, illustrated and claimed.

In the accompanying drawings:—Figure 1 is a side elevation of a sufficient portion of a marine vessel to illustrate the application of the brake of this invention thereto. Fig. 2 is an enlarged fragmentary side elevation partly in section illustrating the manner of mounting one of the brakes in its applied relation to the hull of a vessel. Fig. 3 is a fragmentary horizontal section showing one 40 of the brakes and one of the mounting hangers therefor. Fig. 4 is a similar view showing the brake moved outwardly to its operative position, together with the brake operating means. Fig. 5 is a perspective view 45 of the hanger.

50 As the invention contemplates the use of any desired number of brakes on either side of the hull of the vessel, according to the size of the vessel and other conditions, a description of one of said brakes will answer for the remainder. Each brake consists of

a body 1 shown as of parallelogrammatic formation and resembling an ordinary door, said brake being normally housed in a recess 2 closed by a back or inner wall 3 which excludes water from the hull of the vessel. The outer surface of the brake 1 is normally flush with the outer face of the hull of the vessel indicated at 4.

The brake is pivotally mounted and arranged to swing outwardly and inwardly between upper and lower hangers 5 and 6, respectively, one of said hangers being illustrated in plan view in Fig. 3 where it is shown enlarged at 7 to provide a bearing opening 8 for the adjacent reduced end 9 of a rock shaft 10 forming the hinge pin of the brake. The opening 8 is preferably in the form of a socket extending only part way through the hanger 6 as indicated at 75 the bottom of Fig. 2. The corresponding opening 11 in the top hanger extends entirely through the latter and the shaft 10 is extended above the top hanger 5 where it has fast thereon a crank arm 12. 80

To the crank arm 12 is attached the connecting rod 13 of a steam cylinder 14 under the control of the pilot or engineer who may thereby cause the crank arm 12 to move in the desired direction for either swinging 85 the brake 1 to its resisting or braking position, or in the opposite direction for housing the same in its recess 2.

Under the preferred embodiment of the invention, the lower hanger 6 is set farther 90 forward than the upper hanger 5 which gives an inclination to the rock shaft 10. Under such an arrangement, when the brake 1 swings outwardly, the free edge thereof moves to a certain extent downwardly into 95 denser water and, furthermore, the inclination of the brake, and the forward offsetting of the bottom edge thereof with respect to a vertical line, produces a greater suction or tends to draw the denser water upwardly 100 and in that way obtains a greater braking effect and causes a correspondingly earlier checking of the progress of the vessel.

It will, of course, be understood that the number of brakes on each side of the vessel 105 may be increased or diminished in accordance with requirements such as the size, draft and tonnage of the vessel and furthermore by manipulating the brakes, the course of the vessel may be changed at will, a particularly valuable feature in case of breakage or injury to the rudder. 110

Having thus described my invention, I claim:

The combination with the hull of a marine vessel formed in the outer surface thereof of with a brake receiving recess, of a brake consisting of an imperforate body of parallelogrammatic formation seated flush in said recess, top and bottom hangers for said brake, a rock shaft to which the brake is rigidly fastened journaled in said top and bottom hangers, a crank arm on said rock shaft, and operating means embodying a

cylinder and piston, and a connecting rod actuated by said piston and connected to said crank arm, said rock shaft being inclined with the lower end thereof located in advance of a vertical line passing through the upper extremity thereof. 15

In testimony whereof I affix my signature in presence of two witnesses.

WADE H. HARRISS.
